UNITED STATES PATENT OFFICE.

FREDERICK W. WAKEFIELD, OF VERMILION, OHIO, ASSIGNEE TO THE F. W. WAKEFIELD BRASS COMPANY, OF VERMILION, OHIO, A CORPORATION OF OHIO.

CARBURETOR.

Application filed May 6, 1918. Serial No. 232,691.

To all whom it may concern:

Be it known that I, FREDERICK W. WAKEFIELD, a citizen of the United States, and a resident of Vermilion, county of Erie, and 5 State of Ohio, have invented a new and useful Improvement in Carburetors, of which the following is a specification; the principle of the invention being herein explained, and the best mode in which I have 10 contemplated applying that principle so as to distinguish it from other inventions.

The present improvements, relating as indicated to charge forming devices, or carburetors, as they are commonly termed, for 15 internal combustion engines, have as their object the provision of a device of this sort wherein variations in the suction of the engine will automatically effect the necessary adjustments to provide a uniform charge in 20 the proper amount. A further object is to provide a device that will be simple in construction with no float chamber or float valves, and with a minimum of moving parts elsewhere. To the accomplishment of the 25 foregoing and related ends, said invention, then, consists of the means hereinafter fully described and particularly pointed out in the claims.

The annexed drawings and the following 30 description set forth in detail certain mechanism embodying the invention, such disclosed means constituting, however, but one of various mechanical forms in which the principle of the invention may be used.

35 In said annexed drawing:

Figure 1 is a central vertical section of a charge forming device or carburetor embodying my present improvements; Figure 2 is a similar central vertical section of a 40 portion of such device, the plane of the section being at right angles to that of Figure 1, as indicated by line 2-2 of said Figure 1; and Figures 3, 4, 5 and 6 are transverse sections taken on the horizontal planes indicated by the lines 3-3, 4-4, 5-5 and 6-6 45 of Figure 1.

The body 1 of the carburetor is of generally cylindrical form and may be regarded as divided transversely into two chambers 2 and 3 by a constricted portion 5. The upper 50 portion of these 2 is designed to communicate directly with the engine manifold (not shown), and is normally separated from the lower chamber 3 by means of an outer annular valve 4 that approximately contacts

with the side wall of the chamber at 5, and an inner piston 6 that is adapted similarly to close the interior space defined by such annular valve, it being noted that the aforesaid wall flares outwardly above the line of 60 contact of the annular valve 4 therewith. This valve is adapted to be positively raised from the normal position illustrated in Figures 1 and 2, and held in such raised position by means of an externally operated 65 shaft 7 carrying a pinion 8 that meshes with a rack 9 attached to such valve, which may accordingly be regarded as in the nature of a throttle valve.

Attached to such annular valve by means 70 of two rods 11, so as to be operated in conjunction therewith, are the arms 40 of a second annular valve 12 which is fitted to the interior of the wall of the lower chamber 3 and which in its normal position closes a 75 series of apertures 13 in such chamber wall. As the throttle valve 4 is raised, however, this lower valve is correspondingly raised to admit an increased quantity of air to the interior of the lower chamber, thus constituting an auxiliary air valve in effect.

Rising centrally from the bottom of the lower chamber is a tubular duct 15 that has communication at its lower end through a passage 16 in such bottom wall with the fuel supply duct 17, connection of the latter with the aforesaid passage being controlled by means of a needle valve 18, as clearly shown in Figure 6; while vertically reciprocable within such central duct is a valve comprising a head 19 with a tapering extension 20 that projects into the passage 16, the head, when seated as shown in Figure 1, shutting off the supply of fuel through such passage, but when raised permitting the fuel to pass 95 in graduated amount, as determined by the position of the extension, through notches or grooves 21 formed in the side of such head. The upwardly extending stem, or spindle 22, of the valve is guided in a close-fitting aperture formed in a cored out spider-center 23 which caps the upper end of the duct 15. Such valve-spindle has secured to its upper projecting extremity the aforesaid piston 6, that fits within the annular throttle 100 valve 4, and said spindle is also provided, a short distance above the lower valve 19, with a cylindrical enlargement 25 fitting as a valve within the duct and normally closing a series of apertures 26 formed in the lateral 110

wall of such duct. This valve-like enlargement, however, is pierced longitudinally by a plurality of apertures 27 which leave the portions of the duct above and below the 5 same in substantially unrestricted communication with each other.

Communication with the external atmosphere is provided for the interior of the duct 15 by means of a passage 28 formed in 10 one of the spider arms 29, such passage communicating with the interior of the spider-center 23 and thus with the duct, as clearly shown in Figures 1 and 3.

The bolts 30, it will be understood, merely 15 serve to secure together the several component parts of the casing 1. A set screw 31 may also be provided in conjunction with valve 4, whereby the relative movement of the piston 6 may be regulated, or its upper 20 position limited to correspond with the setting of the first-named, i. e. throttle valve.

Having thus described the construction of my improved carburetor, its mode of operation should be readily apparent. In starting 25 the engine, the throttle, of course, is opened only slightly, this serving to raise the edge of the annular valve 4 a trifle above the spider-center 23, on which it normally seats. The interior of the valve 4 acts as a cylinder 30 for the piston 6 and the suction of the engine will thereupon raise the inner valve 6, and of course correspondingly raise the fuel-valve 19 and at the same time open the apertures 26 in the lateral wall of the duct 15. 35 In this position of the parts the air is drawn largely through the passage 28 in the spider, downwardly through the duct 15 to the apertures just named, where it is commingled with the fuel, sprayed upwardly past the 40 valve 19 through the recesses 21 therein. The mingled air and gasoline, or other fuel, vapor, thence passes upwardly into the upper chamber of the carburetor and to the engine.

45 As more power is desired, the throttle is opened wider, correspondingly raising the auxiliary air valve, and at the same time permitting the fuel supply valve to be raised that much higher, the increased amount of 50 fuel being reduced to the proper degree of richness by the additional air drawn in through the apertures 13 which then passes through the ports 26 into the duct 15. Such fuel, however, is initially mingled, as in the 55 starting stage, with the air drawn through

the spider passage 28, and then intermingled with the auxiliary air supply, insuring thorough vaporization of the fuel and uniformity in the charge as finally drawn past the throttle valve and admitted to the engine. 60

The foregoing construction of carburetor has been found in actual tests to have surprisingly efficient action, this being attributable to the automatic control of the fuel supply by the effect of the engine suction on the inner valve 6, the range of movement of the latter being increased as the throttle valve is raised, and the raising of the latter serving at the same time to admit sufficient auxiliary 65 air to maintain the charge at all times at just the right degree of richness. 70

Other modes of applying the principle of my invention may be employed instead of the one explained, change being made as 75 regards the mechanism herein disclosed, provided the means stated by any of the following claims or the equivalent of such stated means be employed.

I therefore particularly point out and distinctly claim as my invention:—

In a device of the character described, the combination of a tubular casing adapted to be connected with the engine intake at its upper end and having air-inlet openings 80 near the lower end, said casing having an intermediate constricted portion; a central duct in said casing closed at its upper end and having fuel supply connections at its 85 lower end, said duct having lateral apertures communicating with the casing interior and an exterior air-supply connection; an annular throttle valve adapted to seat on said 90 closed duct-end and, in such position, to fill such constricted casing portion; a valve, operatively connected with said annular valve, adapted to control the air-inlet opening in 95 said casing; a valve in lower end of said duct adapted to control the supply of fuel thereto, said valve having a stem extending upward through the upper end of said duct; a suction-controlled valve attached to the 100 upper end of said stem and fitted within said annular valve; and a longitudinally perforated cylindrical valve fitted within said 105 duct and adapted to control the lateral apertures therein.

Signed by me, this 1st day of May, 1918.

FREDERICK W. WAKEFIELD.
